UNITED STATES PATENT OFFICE.

LOWELL H. RICE, OF CHICAGO, ILLINOIS, ASSIGNOR TO METAL SECTIONAL FURNITURE COMPANY, A CORPORATION OF MAINE.

BEVELING-MACHINE.

No. 811,174.

Specification of Letters Patent.

Patented Jan. 30, 1906.

Application filed February 16, 1903. Serial No. 143,534.

To all whom it may concern:

Be it known that I, LOWELL H. RICE, of Chicago, in the county of Cook and State of Illinois, have invented certain new and useful Improvements in Machines for Beveling Bookbinders' Boards and the Like; and I do hereby declare that the following is a full and exact description thereof, reference being had to the accompanying drawings.

This invention relates to machines for beveling or mitering bookbinders' boards—such as cloth boards, tar-boards, pasteboards, or the like, including soft woods and other materials of similar consistency. Such work is at present done largely by hand, a sharp hand-knife being used for the purpose. Such machines as have been designed and constructed for the purpose heretofore have failed in securing a clean even cut by reason of the tendency of the materials to cling and drag on the cutting-surfaces.

My invention consists, first, in the mechanism for perfectly and rapidly executing the bevel.

It consists, second, in the mechanism for executing a like bevel on a number of boards at a single operation.

It consists, third, in the mechanism for automatically clamping a number of boards into the machine for beveling.

It consists, fourth, in the adjustment of the machine for regulating the angle of the bevel.

It consists, fifth, in the mechanism for adjusting the depth of the cut to be made.

It consists, sixth, in the various novel devices and combinations of the same herein illustrated and described, together with their mechanical equivalents, and pointed out with more particularity in the claims appended hereto.

In the drawings, Figure 1 is a perspective view of my machine, taken from the rear. Fig. 2 is a view of the front elevation of my machine. Fig. 3 is a sectional view of my machine, taken through the line X X of Fig. 2 and looking toward the left. Fig. 4 is a sectional plan view of my machine, taken through the line Y Y of Fig. 2. Figs. 5, 6, and 7 are detail illustrations of the automatic clutch which I use.

More particularly described, A designates the frame of the machine, comprising side members A' A', consisting of legs A² A², long

slotted standards A³ A³, and the shelves A⁴ A⁴. These side members A' A' are joined together by the horizontal top member A⁵ and the lower cross members A⁶ A⁷ A⁸ A⁹.

The cutting mechanism of my invention is described as follows: It consists of an upper and movable sharp-edged knife B, fitted within a heavy bar or frame B'. The bar B' is constructed of heavy material, is swung between the standards A³ A³, and fitted with projecting lugs B² B², which slide perpendicularly within the slotted standards A³ A³ and project as to their free ends beyond the outer surface of A³ A³. The lower side of the said bar B' and the one to which the knife B is attached presents a straight surface, but out of horizontal plane, the end nearest to one of the standards A³ being higher than the end nearest the other standard A³. The knife B (a straight sharp-edged tool) is secured to the said bar B' at said lower side by means of bolts B³ B³, and so secured presents a sharp cutting edge in relation to, but out of horizontal plane with, the lower cutting edge B⁴. The lower cutting edge B⁴ is a firm strong bar of approximate rectangular contour extending horizontally between and rigidly secured to the standards A³ A³ near their lower ends. Said bar B⁴ is highly finished as to its top side and also the inner or side nearest the knife B, so as to form for presentation to the said knife B a sharply-defined edge formed by the right-angular contact of the said upper and inner polished sides. The lower edge B⁴ and the upper edge or knife B, being out of horizontal plane, are brought into contact first at one end of the respective edges and from said ends come gradually into contact throughout their length, as do the blades of a pair of shears. The operating mechanism of the said upper knife B is described as follows: To the lugs B² B² on either end of the knife-bar B' are secured by a flexible joint one end of the respective rods C C. The other end of the rods C C are attached by a pivot-joint to the crank-disks C' C' at or near the circumference of said disks C' C', which disks lie on the outside of the respective side members A' A' of the frame and near the bottom. These disks C' C' are secured at their center to the shaft C², which is journaled into the respective side members A' A' near the bottom. The shaft C² is connected with the driving-shaft C³ by means of the gears C⁴ C⁵,

2
attached, respectively, to the shafts C² and C³. The shaft C³ is journaled at its ends onto the rear faces of the said members A' A' and near the bottom C⁶ C⁷. Upon the driving-shaft C³ and intermediate of the side members A' A' the driving-wheel C⁸ revolves. The hub of the said driving-wheel C⁸ extends as to one side C⁹ beyond the side surface of the wheel, and within this projecting part of the hub C⁹ lies the clutching mechanism which connects the driving-wheel C⁸ to the shaft C³ and applies the driving power to the machine.

The clutching device is illustrated in detail in Figs. 5, 6, and 7. Within the hub end C⁹ is fitted a bushing D, which as to its inner surface is ratcheted D' D'. That part of the shaft C³ lying adjacent to said ratchets and that part lying immediately beyond and outside the hub C⁹ is slotted to receive the pawl D². This pawl consists of two parts D³ and D⁴, made, however, of one piece. The width of the part D³ is equal to the diameter of the shaft C³, and the width of the part D⁴ is equal to the diameter of a casing D⁵, which surrounds that part of the shaft C³ which lies between the hub C⁹ and the journal-block C⁶, and which casing is perforated to receive the ends of the part D⁴. Inserted within the slotted shaft the part D³ lies immediately adjacent to the ratchets D' of the hub C⁹, and the part D⁴ lies immediately without the hub and passes through the casing D⁵. Immediately beyond said pawl D² and from the hub C⁹ lies a spring-seated pin D⁶ within a suitable slot in the said shaft C³ and the casing D⁵. D⁶ is provided with a lug D⁷, engaged with the said part D⁴. When the said spring-seated pin is released, it forces one end of the part D⁴ of the pawl beyond the surface of the casing D⁵. Lying without the casing D⁵ and in opposition to the part D⁴ of the pawl D² is a concave cam D⁸, slidingly engaged with a platform D¹¹, affixed to the frame A of the machine. The cam D⁸ is secured to a plate D⁹, which slides within a suitable groove in the surface of the platform D¹¹. The plate D⁹ is in turn attached to a compound foot-lever D¹⁰, the free or power end of which projects from the front of the machine within easy reach of the foot of the operator.

The operation of the clutching device is secured as follows: When out of contact, the drive-wheel turns freely upon the shaft, and the part D³ of the pawl D² lies within the diameter of the shaft C³ and out of contact with the ratchets D' D'. One end of the part D⁴ of the pawl D² lies at the surface of the casing D⁵ and against the face of the cam D⁸. When the power end of the lever is tripped or forced downward by the operator, the cam D⁸ is withdrawn by the operation of the lever D¹⁰ out of contact with the end of the part D⁴ of the pawl D². The spring-post D⁶ then forces

one end of the part D⁴ out and beyond the surface of the casing D⁵, thereby forcing the part D³ of the pawl D² beyond the surface of the shaft C³ and engaging with the ratchets D' within the hub of the revolving driving-wheel C⁸. The shaft C³ is then thrown into action and through it the cutting mechanism. In order to throw the machine out of gear and out of contact with the power or driving wheel C⁸, I provide a coiled spring D¹², 75 which replaces the lever to its original position when the power end is released. When the lever is replaced by the spring D¹², the cam D⁸ is made to slide back into position in opposition to the projecting end of the part D⁴ of the pawl. This projecting end D⁴ is then caught upon the surface of cam D⁸ and gradually forced by the said cam D⁸ back into the casing D⁵. At the same time the part D³ is gradually withdrawn from the ratchets D' and back within the diameter of the shaft C³, throwing the machine out of gear. In order that the machine may come to rest almost immediately when disconnected from the said driving-wheel C⁸, I provide a friction-clamp attached to the shaft C² and held in place by a bearing C¹¹ upon the shaft C³, which clamp is designed to overcome any momentum which the machine may have at the moment of release from the power and 90 stop it at once. A further purpose of this friction-clamp C¹⁰ is to counterbalance the weight of the knife-bar B' and hold the knife B upward and out of contact with the lower knife-bar B⁴ when the machine is out of gear. 100

In order that the machine may be stopped automatically upon the completion of one operation of the knife-bar, I provide a wheel D¹³, secured to the shaft C² and operating in relation with a small roller D¹⁵, which is secured to the lever D¹⁰ near its power end. The rim of the wheel D¹³ is grooved to form a track for the roller D¹⁵. At one point on its rim the wheel D¹³ is provided with a recess D¹⁴. The disks C' C' by one complete revolution 110 perform one complete operation of the machine. Then as the disks C' C' and the wheel D¹³ are attached to and revolve upon the same shaft C² the wheel D¹³ makes one revolution in the completion of one operation of the machine. The wheel D¹³ is of such size that at all points of its circumference except the recess D¹⁴ it will in relation with the roller D¹⁵ hold the power end of the lever downward as forced by the foot of the operator and hold 120 the clutching mechanism in contact. When the roller in the revolution of the wheel D¹³ passes into the recess D¹⁴, the power end of the lever is raised by the operation of the spring D¹² and the machine disconnected from 125 the driving-wheel C⁸, as aforesaid.

The feed-table of my device is new in its construction and is illustrated in the sectional view Fig. 3. It consists of the table E, supported by the blocks E' E², the whole resting 130

upon the shelves $A^4 A^4$ of the side pieces A' A' . The table E is a broad piece of metal or other material, the upper or inner side of which is smooth for holding the board P when being operated upon. The inner and lower edge of the table E lies in close proximity to the cutting edge of the lower cutting-bar B^4 . In order to change or shift the angle of the table E with the plane of the knives B and B^4 , I provide the blocks E' and E^2 . E' is firmly secured to the lower or back side of the table E and presents to the block E^2 a convex surface. E^2 is the lower block and is slidingly engaged with the shelves A^4 A^4 . It presents to the said convex surface of E' a correspondingly-concave surface, and the said convex and concave surfaces of the two respective blocks E' and E^2 have sliding engagement one with the other. The said convex and concave surfaces describe the segment of a circle the center of which is the lower and inner edge of the said table E , the purpose of this being that the plane of the table E may be changed without changing the position of its said lower and inner edge. On the face of the said convex surface of block E' , I provide a number of polished surfaces $e' e' e'$, which form the points of the contact of said block E' with corresponding polished surfaces on the concave surface of block E^2 . In order to hold the blocks E' and E^2 firmly together, I provide clamp-screws $E^3 E^3$, which pass through block E^2 and engage with the block E' at its ends by means of lugs $e^3 e^3$, which clamp in a segmental groove on either end of the said convex surface of said block E' .

Not only is it necessary to provide for the regulation of the angle of the cut to be made, but I must provide a means of regulating the depth of the cut to be made on the board. With the lower and inner edge of the table E lying in contact with the cutting edge of the lower knife B^4 and the table E inclined toward the plane of the knife B it is seen that with the board P to be cut lying against the lower edge of the table E the knife in operation would make a cut through the entire thickness of the board, or inasmuch as the cut is made at an angle the board after being cut would have on the beveled end a sharp edge. This in some instances is undesirable. Therefore I must provide some means of shortening the cut. I do this by providing means of withdrawing the table from the knife by sliding the block E^2 along the shelves A^4 . Block E^2 is clamped to the shelves A^4 A^4 by means of clamp-screws $E^4 E^4$, extending through suitable slots in shelves $A^4 A^4$ and into block E^2 . Upon the release of the said screws $E^4 E^4$ the block E^2 may be moved backward or forward on the shelves $A^4 A^4$, the screws $E^4 E^4$ sliding along the slots in the shelves $A^4 A^4$. By this movement the table E is moved backward and away from the cutting

edge of B^4 , thereby shortening the cut to be made upon the board P , or forward, and thereby lengthening the cut. This movement of the block E^2 is controlled by adjusting-screws $E^5 E^5$, which extend through the studs $E^6 E^6$, secured to the shelves $A^4 A^4$, and into sockets in the rear face of E^2 . On the rear or lower face of the table E , I provide a suitable handle e , whereby the angle of the said table can be changed and regulated by tilting the table upon the release of the clamp-screws $E^3 E^3$.

When the board P is placed upon the table E , some device must be used to hold it in place while the operation of beveling is being executed. For this purpose I provide an automatic clamp, described as follows: F represents the clamp proper and consists of a heavy piece of material which extends between the side standards $A^3 A^3$ and slides upward and downward within suitable grooves arranged upon the inner faces of the said standards $A^3 A^3$. The inner face or the one extended toward the knife B is smooth and lies parallel and adjacent to the said knife B . The clamp F presents to the board P at its lower end an angular face which will approximately register with the board P as placed upon the angular table E . The clamp sliding freely within the said grooved standards $A^3 A^3$ is of such weight that some means must be provided to hold it in an upward or retired position while the knife B is out of operation and while the board P is being inserted or removed. I therefore design two or more arms $F' F'$, extending upward from the upper end of the clamp F and through suitable apertures in the top piece A^5 . I also provide studs $B^5 B^5$ of like number and corresponding position to the arms $F' F'$, which studs extend upward from the knife-bar B' and through the said top piece A^5 . They are turned at right angles at their upper ends and perforated to receive the upper ends of the arms $F' F'$, which pass through such perforations in the studs $B^5 B^5$ and are fitted with shouldered heads $F^2 F^2$, which prevent the arms $F' F'$ from being withdrawn from the perforated studs $B^5 B^5$.

When the machine is set in operation and the knife-bar B' starts on its downward movement, the studs $B^5 B^5$ move downward, thereby releasing the arms $F' F'$ and permit the clamp F to also move downward. The lower edge of the clamp F extends in its suspended position below the knife B , so that in operation the clamp F reaches the board P before the knife B does and clamps it for the cutting. When the operation of cutting is completed and the knife-bar B' passes upward to its retired position, the studs $B^5 B^5$, which have been sliding on the arms $F' F'$ in the downward movement after the clamp F has stopped on the board P , catch the heads $F^2 F^2$ as they move upward and lift the clamp F .

F away from the board P and to its retired position.

In order to facilitate the downward movement of the clamp F, I provide a number of coiled springs F³ F³, seated upon suitable pins extending upward from the upper face of the clamp F. These springs are shoudered at their lower end against the upper face of the said clamp F and at their upper end against studs protruding from the inner faces of the standards A³ A³.

In consideration of the variation of the style and thickness of the boards to be operated upon I find it necessary to provide some form of adjustable back guide for the boards, and it must be of such size and style that it will serve to hold one or more boards, as may be desired. This improvement I describe as follows: My guide consists of two plates G and G', lying to the rear of and just below the knife B. The top edges of the plates G and G' are cut to such an angle as to correspond with the angle of the knife B. The plate G lies immediately in the rear of the knife B and extends between the faces of the standards A³ A³ and is held in place by engagement with the plate G'. This plate G' lies parallel to and to the rear of the plate G or farther from the knife B and slides within suitable grooves upon the inner faces of the standards A³ A³. It is supported by hinged arms G², attaching it to the knife-bar B'. The plate G is adjustably secured to the plate G' by a series of adjustable screws G³ G³, passing through plate G' and socketed into the plate G. Said plate G is held firmly in place by a series of spring-seated posts G⁴ G⁴. The said posts G⁴ G⁴ are attached as to one end to the plate G, and as to the other end they are free and slide within suitable perforations in plate G'.

By the operation of the adjustable screws G³ G³ the plate G can be advanced or retired and regulated as a guide for the board P. When the board P is placed upon the table E, it slides downward until its lower end strikes the guide-plate G, which holds it until the clamp F descends to clamp it. Any number of boards P may be inserted one upon the other, and the plate G will hold them all till they are clamped.

The top edge of the plates G and G' are cut parallel to the knife B and lie a short distance beneath said knife B in order that the shaving from the cut may have an outlet. The shaving falls over the guide-plates G G' and outward. To prevent the shavings from falling between the guide-plates G G', I provide a cover-plate G⁵, which is secured to plate G and extends over plate G', but is not secured thereto.

The purpose of hinging the arms G² is that the knife B may be easily removed from the machine for sharpening. The arms G² are unbolted from the bar B' and thrown out

ward and downward, thereby permitting the knife B, which has been released from the bar B', to be removed.

The operation of my machine is described as follows: In the normal position, with the machine at rest and out of connection with the motive power, the knife B rests at the top of the frame of the machine and away from the knife B⁴, held there by the action of the friction-clamps C¹⁰ C¹¹. The clamp F by its connection with the knife-frame B' is likewise held in a suspended position and away from the feed-table E. The board P to be beveled is placed upon the table E, which is adjusted to the desired angle, and is made to slide forward until it rests against the back guide G, which is adjusted as desired. The operator then trips with his foot the lever D¹⁰ and through its operation throws the machine into connection with the motive power. The machine is thrown into action and the knife B and the clamp F move downward. The clamp F reaches the board P on the table before the knife B does and by its own weight and the action of the springs F³ clamps the board P while being cut. The knife B then strikes the board at one side and in its downward movement executes the bevel from one side to the other, as would a pair of shears. The shaving falls over the shield G⁵ and out backward. The knife B is then returned by the action of the disks C' C' to its original position and in ascending catches the clamp F and lifts it free from the board P. When the knife B and clamp F shall have reached their original position, the wheel D¹³ shall have completed one revolution and the roller D¹⁵ moves into the recess D¹⁴ and the lever D¹⁰ assumes its original position, thereby automatically releasing the machine from the motive power. When two or more boards are to be beveled at the same time, they are placed upon the table E, one upon the other, and made to slide against the back guide G, which is of such width as to accommodate any desired number.

While I describe particularly one form of clutching device, any suitable form of clutch may be used to effect the connection with and release from the motive power. Likewise other forms of gears and frames may be used, those described herein being merely preferable to me.

I claim as my invention—

1. A feed-table for a beveling-machine consisting of a table supported by a block superposed upon another block and which blocks are adjustably fitted to each other by respective convex and concave surfaces, and means for actuating said blocks.

2. In a machine for beveling millboards and the like, the combination with, a feed-table, a back guide, a clamp and means for actuating said clamp, of means for cutting one or more millboards comprising a horizontal

straight-edge, and a knife set at an angle with said straight-edge, and coacting with the same and movable in a perpendicular plane, and means for lowering and raising said 5 knife.

3. In a machine for beveling millboards and the like, the combination with a horizontal straight-edge or ledger-blade, and a corresponding knife set on an angle to said ledger-blade, and movable in a perpendicular plane, and means for actuating said movable knife, of a feed-table comprising a flat table supported by a block superposed upon another block and which blocks are adjustably fitted to each other by respective convex and concave surfaces, and means for actuating said adjustable blocks.

4. In a machine for beveling millboards and the like, the combination with cutting-knives, and means for operating the same of a feed-table supported by a block superposed upon another block, and which block in turn rests upon the frame of the machine; the said blocks being adjustably fitted to each other 25 by a respective convex and concave surface, which forms the segment of a circle of which the edge of the feed-table lying nearest to the cutting-plane is the center, and means for securing said blocks together.

5. In a machine for beveling millboards and the like, the combination with cutting-blades, one stationary and the other movable in a perpendicular plane, a feed-table and means for actuating said blades, of an adjustable back guide, consisting of two parallel plates, one of which is secured to the frame of the said movable knife, and the other adjustably attached to the said secured 35 plate and extending toward the cutting-plane from that side of the cutting-plane op-

posite to the feed-table, and means for actuating said adjustable guide.

6. In a machine for beveling millboards and the like, the combination with cutting-knives, an adjustable feed-table, and means 45 for operating said knives and means for actuating said feed-table, of a back guide consisting of two plates lying opposite to said feed-table and on the opposite side of the cutting-plane of said knives, one of said plates being 50 secured to the frame of one of the said knives and the other lying between said secured plate and the cutting-plane of said knives and being adjustably secured to said secured plate, and means for advancing said adjustable plate toward and retiring it from said cutting-plane.

7. In a beveling-machine, a feed-table consisting of a table secured at its rear end to a block fitted with a convex surface, the forward end of said table being free; a block secured to the frame of said machine and fitted with a concave surface, said convex and concave surfaces having adjustable engagement with each other.

8. In a beveling-machine, a feed-table consisting of a table having its forward end free from securement, and being secured at its rear end to a block superposed upon another block, which latter block is attached to the 70 frame of said machine, and which blocks are fitted respectively with convex and concave surfaces at the point of contact with each other, and means for adjusting said blocks in their relation with each other, and with the 75 frame of the said machine.

LOWELL H. RICE.
